CLAIM

The ornamental design for a motion sensor lamp adaptor, as shown and described.

DESCRIPTION

FIG. 1 is a front and right side perspective view of a motion sensor lamp adaptor showing our new design;

FIG. 2 is a front elevational view thereof;

FIG. 3 is a left side elevational view thereof;

FIG. 4 is a top plan view thereof;

FIG. 5 is a rear elevational view thereof;

FIG. 6 is a bottom plan view thereof;

FIG. 7 is a left side elevational view thereof, with the motion sensor in an alternate position;

FIG. 8 is a left side elevational view thereof, with the motion sensor in an alternate position; and,

FIG. 9 is a front elevational view thereof, with the motion sensor in an alternate position.

The broken-line disclosure of elements in the views are understood to be functional aspects of the article in which the design is embodied and form no part of the claimed design.
